UNITED STATES PATENT OFFICE.

JULIUS H. SCHLAFLY, OF CANTON, OHIO, ASSIGNOR TO THE CANTON CULVERT COMPANY, OF CANTON, OHIO, A CORPORATION OF OHIO.

SHEET-METAL STRUCTURAL SECTION.

1,141,417.

Specification of Letters Patent.

Patented June 1, 1915.

Application filed August 17, 1914. Serial No. 857,045.

To all whom it may concern:

Be it known that I, JULIUS H. SCHLAFLY, a citizen of the United States, residing at Canton, in the county of Stark and State of Ohio, have invented a new and useful Sheet-Metal Structural Section, of which the following is a specification.

My invention relates to improvements in sheet metal structures and while applicable to structures for various purposes has special reference to the construction of sheet metal structural sections for silos and the like.

The objects of the invention are, to generally improve structures of the character mentioned, to provide a silo or the like which will be strong and durable and thoroughly air and water tight and thus adapted to thoroughly preserve and retain its contents, and to provide a knock-down or sectional construction wherein the various parts or sections are so constructed as to be interchangeable, thus making the erection of the device an easy matter in that said sections need not be put together in any one, predetermined order or arrangement and the means of connection for the various sections being simply and readily understood by unskilled workmen.

Additional objects are the provision of air and water tight joints between the various sections, the strengthening of the edges of the sections so as to brace the joints and the protection of the joints by integral protecting flanges.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made without departing from the spirit or sacrificing any of the advantages of the invention.

In the drawings: Figure 1 is a perspective view of a sheet metal structural section constructed in accordance with my invention. Fig. 2 is a fragmentary view of a plurality of sections assembled. Fig. 3 is a fragmentary perspective view illustrating the manner of connecting the sections. Fig. 4 is a similar view showing one section removed. Fig. 5 is a view similar to Fig. 3, showing the interior views of the sections. Fig. 6 is

an edge view of one of the sections. Fig. 7 is a fragmentary plan view of a portion of the top edge of a section. Fig. 8 is a fragmentary sectional view on line 8—8, Fig. 6. Fig. 9 is a plan view of the blank from which a section is formed.

Similar numerals of reference indicate corresponding parts throughout the several figures of the drawings.

Referring more especially to the construction disclosed in the accompanying drawings each section 1 is substantially rectangular and is preferably arranged with its long dimension horizontally. Each section is curved in accordance with the desired circumference of the silo desired to be constructed and two adjacent edges preferably the top and one side edge are provided with the plain out-turned integral flanges 2 and 3, respectively. The top flange 2 is provided with the beveled edge 4 at either extremity by means of which the outer edge of the flange 2 is of greater length than the inner edge 6 thereof, thereby forming overhanging angular extensions 7 at either end of the flange 2, said extensions being adapted to overlap those of the next adjacent sections when the sections are assembled as shown more clearly in Fig. 3 of the drawings. The opposite or bottom and other side edge are provided with the outturned flanges 8 and 9 respectively, said flanges 8 and 9 being provided with integral auxiliary protecting flanges 10 and 11 respectively, said flanges 10 and 11 extending at right angles to the flanges 8 and 9 and lying in planes parallel with the body portion of the section. The flanges 2, 3, 8 and 9 are all provided with bolt apertures 12 to receive bolts 13 for fastening the sections together. The lower flange 8 is provided with a beveled edge 14 at either extremity by means of which, the outer edge 15 of the flange 8 is of greater length than the inner edge 16 thereof. Overhanging angular extensions 17 are thereby formed at either end of the flange 8, said extensions being adapted to overlap those of the next adjacent sections when the sections are assembled as shown more clearly in Fig. 3 of the drawings. The upper and lower edges 18 and 19 respectively of the flange 9 and the upper and lower edges 20 and 21 respectively of the flange 3 are slightly beveled as shown in the drawings. By this construction the flanges 9 and 3 are slightly 110

tapered outwardly allowing sufficient space between the upper and lower beveled edges of the flanges and the adjacent horizontal flanges to permit the overlapping of the extremities of the horizontal flanges. In Fig. 5 is shown in dotted lines the position assumed by the extremity of one of the horizontal flanges after it is lapped over the extremity of the adjacent horizontal flange 10 and it will be seen that, from an inspection of this figure, sufficient space is left between the lower beveled edge 9 and the horizontal flange 8 to allow the flared extremities of the adjacent horizontal flanges to be inserted 15 therebetween.

By reference to Figs. 3 and 4 of the drawings it will be seen that in joining adjacent sections in any one tier the flange 9 is brought face to face with the flange 3 of an 20 adjacent section, the flange 11 formed integral with the flange 9 extending over the edge of the flange 3 and thus protecting and covering the joint. Between the flanges 3 and 9 packing of any well known material 25 may be arranged, if desired before drawing up the bolts 13, said packing helping to produce an air tight joint, although it is not necessary to use the packing and in the accompanying drawing no packing is shown.

30 When each tier has been connected and arranged in place the top plain flange 2 of the various sections constituting the tier will form an annular outward extending flange upon which the bottom flanges 8 of the sections of the superadjacent tier are adapted 35 to rest. Here again packing may be employed if desired in order to form a tight joint and bolts 13 may be used to fasten the flanges together. The protecting flanges 10 of the various sections extend over the flanges 2 as will be especially noted with 40 reference to Figs. 3 and 4 to produce a dependent water drip adapted to carry any water over and beyond the joint. An important feature of the construction is the 45 strengthening and bracing effect produced by the flanges 10 and 11. By reference to Figs. 3 and 4 of the drawings it will be noted that when the outstanding flanges 2 and 8 and 3 and 9 have been connected to 50 deform the horizontal and vertical joints described, said flanges serve to thoroughly brace and strengthen the wall of the silo so long as said flanges are maintained in true 55 outstanding position. The flanges 10 and 11 act as braces for the said outstanding joint flanges, hold the outer edges of said flanges in true alignment and thoroughly brace them against bending as well as 60 against relative movement which would weaken the structure and loosen the joints.

The upper and lower flanges 2 and 8 are outwardly beveled at their outward extremities so that they will overlap the flanges of 65 the adjacent sections upon either side in the

same tier, for the purpose of producing a tighter and more air tight joint than would be possible if the flanges were cut off straight at their ends. By the construction shown here the vertical edges of adjacent sections 70 may be drawn tightly together and the flanges are held tightly together by means of the bolts thus producing an air tight joint even without the use of packing material, it being only necessary to use one or 75 two coats of paint upon the inside surface of the sections in order to produce an air tight silo. This is an important feature in the building of silos as in cases where there are loose joints in a silo and the outer air is 80 allowed to enter and come in contact with the ensilage the entire contents of a silo is often ruined by fermentation.

Although the drawings and above specification disclose the best mode in which I 85 have contemplated embodying my invention I desire to be not limited to the details of such disclosure, for, in the further practical application of my invention, many changes 90 in form and construction may be made, as circumstances require or experience suggests, without departing from the spirit of the invention, within the scope of the appended claims.

95 I claim:

1. In a silo, a plurality of sections, each section comprising a rectangular sheet metal body portion provided at its edges with outstanding flanges, the flanges of adjacent sections abutting each other, the outer edges of 100 the vertical flanges of a section being shorter than the distance between its horizontal flanges, the outer edges of the horizontal flanges of a section being longer than the 105 distance between its vertical flanges, whereby the horizontal flanges of adjacent sections overlap each other at their ends.

2. In a silo, a plurality of sections, each section comprising a rectangular sheet metal body portion provided at its edges with vertical and horizontal, simple, outstanding flanges and compound flanges including outstanding portions and auxiliary brace portions lying in planes transverse to said outstanding portions, the outer edges of the 110 vertical flanges of a section being shorter than the distance between its horizontal flanges, the outer edges of a horizontal section being longer than the distance between 115 its vertical flanges, whereby the horizontal flanges of the adjacent sections overlap each other at their ends, the simple, outstanding flanges of each section connected to the outstanding portions of the compound flanges 120 of adjacent sections to form connecting seams and said auxiliary portions extending over and protecting said seams and bracing said outstanding, simple flanges and outstanding portions against distortion.

3. In a silo, a plurality of sections, each 125

section comprising a rectangular sheet metal body portion provided at its edges with vertical and horizontal marginal, outturned, connecting flanges, the outer edges of the vertical flanges of a section being shorter than the distance between its horizontal flanges, the outer edges of the horizontal flanges of a section being longer than the distance between its vertical flanges, where-
5 by the horizontal flanges of adjacent sec-
tions overlap each other at their ends, the connecting flanges of adjacent sections abut-
ting each other, means for fastening the

abutting flanges together to form seams and one of the flanges of each seam being pro-
15 vided with an auxiliary flange extending at right angles to the abutting flange of said seam and covering the joint between said abutting flanges.

In testimony that I claim the above, I 20 have hereunto subscribed my name in the presence of two witnesses.

JULIUS H. SCHLAFLY.
